J. H. MYRE

SLIDE GAME MECHANISM

Filed Sept. 20, 1926

UNITED STATES PATENT OFFICE.

JAMES H. MYRE, OF DETROIT, MICHIGAN.

SLIDE-GAME MECHANISM.

Application filed September 20, 1926. Serial No. 136,513.

My invention relates to a new and useful improvement in a slide game mechanism in which a tiltable supporting member is used for precipitation on to an inclined slide upon the player of the game affecting a portion of the mechanical parts, this operation being effected through exercise of skill of the player. I am aware that games of this class have been previously developed, and in some of the games an animal or fowl is positioned on the tilting platform and precipitated down the slide. The present invention, although the mechanism illustrated may be used for other purposes as well, is adapted primarily for use in a game of this class in which a fowl is precipitated on to the inclined platform. It has been found that when the fowl is placed on the swingable platform or the container mounted thereon that at the time of operating the mechanism so as to effect precipitation of the fowl on to the incline, mechanism is such that the precipitation is not abrupt and quick enough for it to overcome the resistance which the fowl brings about through a spreading of its wings so as to engage the sides of the container or compartment in which it is positioned. In the present invention the mechanism is shown where this disadvantage is overcome by having a receptacle or container which is abruptly moved and brought closely enough to a vertical position to precipitate the fowl from the compartment or container regardless of the spreading of the wings of the fowl.

Another object of the invention is the provision of a mechanism which is simple in structure, economical of manufacture, and highly efficient in use. Another object of the invention is the provision of a tiltable platform cooperating with an inclined slide so arranged and constructed that when moved to tilted position the platform will be brought to rest at a position so as to be spaced from the incline.

Another object of the invention is the provision of a plurality of targets or movable bodies which must be successively operated in order to affect a portion of the tilting mechanism.

Other objects will appear as hereinafter.

The invention consists in the combination and arrangement of parts hereinafter described and claimed.

The invention will be best understood by a reference to the accompanying drawings

which form a part of this specification and in which,

Fig. 1 is a perspective view of the invention with a part broken away.

Fig. 2 is a front elevation of Fig. 1 with a part broken away.

Fig. 3 is a fragmentary sectional view taken on substantially line 3—3 of Fig. 2.

Fig. 4 is a sectional view taken on substantially line 4—4 of Fig. 2 with parts broken away.

Fig. 5 is a top plan view of the target or movable actuating members.

Fig. 6 is a view taken on substantially line 6—6 of Fig. 5 showing parts in section and parts in side elevation.

As shown in the drawings the invention comprises a base 9 projecting upwardly from which is a rectangular frame 10, this rectangular frame being positioned on the forward end of the platform 9 which ordinarily is retained in elevated position by suitable supports. The upper portion of the rectangular frame 10 is provided at its forward side with a suitable screen 11. Projecting upward from the platform adjacent the rear side is a bench 12, the side walls being connected by cross members 13, 14 and 15. Hingedly connected to the forward side of the cross member 13 adjacent its upper edge is the bottom wall 16 of a receptacle or container which is provided with side walls 17 and 18, a top wall 19 and a swingable rear wall or door 20 provided with a suitable latch 21. It will be noted that the receptacle is pivotally connected adjacent its rear end so that it has a tendency to tilt into the position shown in dotted lines in Fig. 3 in response to gravitation. Mounted on an upwardly projecting support 22 which extends upwardly from the base 9 is an electrically operated latch mechanism 23 connected by the wires 24 and 25 to a suitable source of electrical energy. Upon a closing of the circuit through the wires 24 and 25 the latch mechanism is operated to release the receptacle so that it may be moved to tilting position.

The specific structure of this latch mechanism forms in itself no specific part of the present invention, and is of a type which is well-known.

Mounted on the member 14 as shown in Fig. 3 is a housing 26 in which is positioned a plunger 27 actuated by the spring 28 to force the receptacle into tilted position when

the latch mechanism is released. The wire 25 is connected to a contact 26', this contact 26' being adapted for engaging the metallic plate 27' positioned on the bottom 16, this metallic plate establishing electrical connection between the contact 26' and the contact 28', this contact 28' being suitably connected by the wire 25' to a contact 29 which is mounted on a suitable support 30. This support is contained within a housing, the front wall of which is provided with a plurality of openings 31. Through these openings 31 the player throws a ball or similar article so as to strike leg 32 and the L shaped supports which are positioned in the housing directly in front of the opening 31, the base 32' being hinged connected to a base 33 of the housing. Carried on the leg 32 is a metallic plate 34 which when the L shaped member is moved to the position shown in dotted lines in Fig. 6, serves to establish connection between the contact 29 and the contact 29'. These L shaped members are as shown in Fig. 5 mounted in a row so that as each successive contact 34 carried by the leg 32 of the L shaped members is brought into horizontal position the contact 29 is ultimately connected electrically with the contact 29'', this contact 29'' being connected by the wire 25'' to a suitable source of electrical energy.

It is believed apparent that the targets which consist of the L shaped members may be placed in desired distances from, or location relative to, the location of the platform 9. When the players throwing the balls or other objects through the openings 31 have moved each of the L shaped members into the position shown in dotted lines in Fig. 6, the circuit will be closed to the electrical latch 23 provided the receptacle 16 is in the position shown in full lines in Fig. 3. When this circuit is closed the latch will release the receptacle 16 and permit its tilting to the position shown in dotted lines in Fig. 3. Upon tilting to the position shown in dotted lines in Fig. 3 the circuit will again be broken leading to the latch mechanism 23 so that the danger of burning out the coils in the latch mechanism will be eliminated. The fowl, which may be a duck, or the like, positioned in the receptacle 16 will be precipitated outwardly from the forward end of the receptacle on to an incline or chute 35 which is supported by suitable rests 36 and 37 mounted on the base 9. This chute or incline 35 is provided with side flanges 35' and 35'' and preferably is directed to a tank of water so that the duck is slid into the tank of water.

Projecting upwardly from the support 37 and extending above the upper edge of the upper end of the chute 35 is an abutment 36' which engages the bottom 16 of the receptacle and prevents the end of the bottom 16

of this receptacle from engaging the chute 35 so that the fowl in being precipitated from the receptacle is not moved gently on to the incline, but is given a sufficient fall to cause the beginning of its downwardly sliding movement, thus assuring a sliding of the fowl downwardly on the chute to its lower end. It will be noted also that the receptacle is checked in its downward swinging movement by the abutment 36', thus terminating abruptly its downward swing and giving to it a jar for assisting in the checking of the fowl.

The mounting of the receptacle in this manner has proven most efficient and overcomes the disadvantages generally inherent in a device of this kind where a fowl or other animal is used.

The target mechanism is also one which adds to the attractiveness of the mechanism as a game to be played in that it is necessary for the player, through the exercise of skill, to establish the contacts by rocking a predetermined number of targets. In the drawings I have shown five of these targets, but it is believed apparent that the number may be varied at will.

Rockingly mounted on the support 30 at opposite sides are levers 52 and 53. A rod 54 is connected pivotally to one of these levers and extends to a position accessible to the operator. A rod 55 connects the levers 52 and 53 so that after the L shaped targets have been moved to the position shown in dotted lines in Fig. 6, the operator, by rocking the levers 52 and 53 on their pivot, will, through engagement of the rod 55 with the targets, serve to move them to the position shown in full lines in Fig. 6. A spring 56 serves to retain the levers 52 and 53 in the inclined position shown in Fig. 6.

While I have illustrated and described the preferred form of my invention, I do not wish to limit myself to the precise form of structure shown, but desire to avail myself of such variations and modifications as may come within the scope of the appended claims.

Having thus described my invention what I claim as new and desire to secure by Letters Patent is:

1. A game mechanism of the class described comprising a support; an inclined chute extending downwardly from said support; a container swingably mounted and projecting at its forward end over the upper end of said support; and means, releasable at will, for preventing swinging movement of said container, said container, upon swinging movement to its downward position, terminating with its base position above the base of said inclined chute.

2. A game mechanism of the class described comprising a support; an inclined chute extending downwardly from said sup-

port; a container swingably mounted and projecting at its forward end over the upper end of said support; and means, releasable at will, for preventing swinging movement of 5 said container, said container, upon swinging movement to its downward position, terminating with its base positioned above the base of said inclined chute and at an incline thereto, the incline of the base of said container approaching more closely to the vertical than the incline of said chute.

3. A game mechanism of the class described comprising a supporting member; an inclined chute mounted on and projecting 15 downwardly from one side of said supporting member; an abutment member on the upper end of said chute projecting above the upper edges thereof; a container swingably mounted on said supporting member; releasable means for retaining said container in horizontally disposed position, said container, upon swinging movement into downward position, engaging with its base the upper edge of said abutment member, the base 20 of said container terminating above the base of said chute and being more inclined to the vertical than the base of said chute.

4. In a device of the class described a wall forming member provided with a plurality 25

of openings; L shaped members swingably mounted at the end of their base and adapted normally for retaining the leg thereof in vertical position positioning in alignment with one of said openings; a plurality of 30 separate contacts; a contact on the leg of each of said L shaped members, said contact adapted, upon movement of said leg to horizontal position, for closing electrical connections between an adjacent pair of said first mentioned contacts.

5. In a device of the class described a wall forming member provided with a plurality of openings; L shaped members swingably mounted at the end of their base and adapted normally for retaining the leg thereof in vertical position positioning in alignment with one of said openings; a plurality of 35 separate contacts; a contact on the leg of each of said L shaped members, said contact adapted, upon movement of said leg to horizontal position, for closing electrical connections between an adjacent pair of said first mentioned contacts; and manually operable means for moving said L shaped members into normal position.

50 In testimony whereof I have signed the foregoing.

55 JAMES H. MYRE.
